UNITED STATES PATENT OFFICE.

WILLIAM BLUME, OF SCRANTON, PENNSYLVANIA.

BUGGY-TOP.

SPECIFICATION forming part of Letters Patent No. 374,925, dated December 20, 1887.

Application filed August 26, 1887. Serial No. 247,894. (No model.)

To all whom it may concern:

Be it known that I, WILLIAM BLUME, a citizen of the United States, and a resident of Scranton, in the county of Lackawanna and State of Pennsylvania, have invented certain new and useful Improvements in Buggy-Tops, of which the following is a specification.

My invention relates to that class of folding carriage-tops in which the front bow is omitted for convenience in passing into or out of the carriage when the top is raised, and in which the front section is adapted to fold to furnish a sun or storm hood when desired. Its object is to cheapen the construction of this class of tops, and provide one that is more easily operated and less liable to injury in use.

The invention consists in the peculiar construction and combination of the parts, all of which will be first fully described in connection with the accompanying drawings, and then particularly referred to and pointed out in the claims.

Referring to the drawings, in which like parts are represented by similar reference-letters wherever they occur throughout the various views, Figure 1 is a side elevation of a buggy-seat having my top-frame attached, the frame being shown in its raised position, the hood being also shown extended. Fig. 2 is a similar view with the hood dropped down. Fig. 3 is a similar view of the folded top. Fig. 4 is a front elevation of the front bow of the hood. Fig. 5 is a vertical sectional view, drawn to full size, through one of its downwardly-projecting arms; and Fig. 6 is a vertical transverse section of the same through line x x , drawn to half size.

The two bows A and B are of ordinary construction, and are pivoted to the shifting-rail of the buggy-seat C in the usual manner. The top-props D extend diagonally from the rear prop-blocks of the shifting-rail to near the top of the front bow, A, being pivoted at d to said bow in the usual manner, and provided with the customary rule-joint at d' . From the same pivot at d hinged brace-arms E extend to the downwardly-extending arms of the hood-bow F, to which they are pivoted at f . The top or horizontal portion of the front hood-

bow F is connected to the front bow A by flat metal straps G, which are hinged at g , to permit the bow to be folded down, as shown in Figs. 2 and 3. The ends of the bow F have dovetailed tenons to receive the rubber cushions H, which are sprung over them and secured by nails, as clearly shown in Fig. 5. These cushions have concave depressions on their under sides corresponding to the form of a cross-section of the vertical arms of the bow A. The purpose of these cushions is to protect the arms of bow A from injury when the hood is folded down.

To prevent the bow F from getting out of shape, and to insure the cushions always coming true against the arms of bow A, I bind the bow either upon one or both sides with a metal strip, F'. The bows A and B are connected on top by flexible straps I, of which there may be any desired number. The back bow, B, is connected to the back of the seat by two thin, broad, metal spring-straps, J, one upon each side.

It will be seen that the arch of the hood-bow F is precisely the same in shape as the front bow used in the common folding tops, the only difference being that the lower arms of the common bow, which reach to the front bolster of the shifting-rail, are in this case partially cut away, and the portions of the loose ends remaining are provided with the rubber cushions H. By this means the top is more easily and neatly trimmed and keeps its shape better than in the forms in which the front bow curves in a horizontal instead of in a vertical plane when the top is raised.

What I claim is—

1. The combination, substantially as specified, of the pivoted bows A B and hinged braces D, the bow F, connected to the bow A by braces E and hinged straps G, to fold independent of said bow A, and the rubber cushions H, to protect the arms of bow A.

2. The combination, in a folding buggy-top, of the bows A B and bow F, having cut-away arms, the braces D, for supporting the bows A B, the hinged braces E and hinged straps G, for connecting the bows A and F and admitting of the hood turning down independent of the top, the flexible straps connecting the bows A

and B, and the spring-metal straps connecting the bow B to the buggy-seat, substantially as and for the purpose set forth.

3. The combination, substantially as specified, of the buggy-top bows A B, pivoted to the shifting-rail, the hood composed of the bow F, braces E, straps G, and elastic cushions H, the said bow F having the metal binding-strip F',

and the cushions H having the lower concave ends to fit over the front of the bow-arms A, to for the purpose set forth.

WILLIAM BLUME.
